The ornamental design for a fitting support, as shown and described.

DESCRIPTION

In a preferred embodiment, the nature of this product is as a fitting support primarily useful for serving as a decorative finish for plumbing or accessory fittings.

FIG. 1 is a left, top, front perspective view of a fitting support embodying my new design;

FIG. 2 is a front elevational view thereof, the right side, left side, and rear elevational views being identical to the front elevational view shown; and,

FIG. 3 is a top plan view thereof.

The broken line representation of a hole in FIGS. 1 and 3 is for the purpose of illustration only, and forms no part of the claimed design.
